J. B. KIRBY.

VALVE OPERATING DEVICE FOR INTERNAL COMBUSTION ENGINES.

APPLICATION FILED APR. 12, 1919.

1,405,597.

Patented Feb. 7, 1922.

UNITED STATES PATENT OFFICE.

JAMES B. KIRBY, OF CLEVELAND, OHIO.

VALVE-OPERATING DEVICE FOR INTERNAL-COMBUSTION ENGINES.

1,405,597.

Specification of Letters Patent. Patented Feb. 7, 1922.

Application filed April 12, 1919. Serial No. 289,616.

To all whom it may concern:

Be it known that I, JAMES B. KIRBY, a citizen of the United States, residing at Cleveland, in the county of Cuyahoga and State of Ohio, have invented a certain new and useful Improvement in Valve-Operating Devices for Internal-Combustion Engines, of which the following is a full, clear, and exact description, reference being had

10 to the accompanying drawings.

This invention relates to internal combustion engines such as are used on automobiles, tractors, and like devices and has for its general object the provision of means 15 for increasing the efficiency of the valve-operating devices without rendering the same noisy, or, conversely, of reducing the noise of the engine without detracting from its efficiency.

20 In expensive makes of automobiles, and in some other installations, great pains and expense are incurred in order to obtain a silent motor combined with an efficient operation, and while the poppet valve type is

25 preferred upon the score of efficiency, simplicity, manufacturing expense, longevity, and ease of repair, it has hitherto been found impossible to avoid a certain amount 30 of noise and some makers have even de- parted from this type of motor for that reason.

The noise of a properly designed and muffled engine is almost entirely due to the play or looseness necessarily left be- 35

tween the lift-rod and the valve stem, re- gardless whether these parts engage directly as in the L-head or T-head engine or through the agency of a rocker arm as in the I-head motor; for unless a certain minimum de- 40 gree of lost-motion be permitted, the valves

will not close completely, particularly when the parts become heated, and the slightest 45 excessive looseness produces a highly audi- ble hammering. An acceptable compromise between the considerations of noiselessness

and efficiency is the basis which is com- monly sought, and salesmen engaged in demon- strating expensive cars frequently make a practice of adjusting the valve tappets 50 every day with the most extreme care so as to secure noiselessness, notwithstanding that a slightly increased clearance produces a marked augmentation of power.

The object of this invention is the pro- vision of a simple and compact device to 55 be interposed at some point in the operating mechanism which shall permit the desired

lost-motion without the loss of contact between metal surfaces and thus wholly eliminate any noise at this point; and the essence of the invention resides in the employment 60 of a link-connection or toggle-joint between the members, and arranged in such wise as to lift or displace the valve when straightened and to take up the back-lash when deflected.

65

In the drawings accompanying and forming a part of this application, I have illustrated several embodiments of my said invention, although it will be understood that these constitute only a small number of the 70 many mechanical forms in which my inventive idea can be embodied. In these drawings, Fig. 1 illustrates my improvements as applied to a typical valve-in-head motor; Fig. 2 is a longitudinal sectional 75 view of the connecting device; Fig. 3 is a similar sectional view of a modified form of the device; Fig. 4 is a front elevation of the device shown in Fig. 3; Fig. 5 illustrates my improvements as incorporated directly 80 in the rocker of a valve-in-head motor; Fig. 6 is a top plan view of the rocker shown in Fig. 5; Fig. 7 illustrates one mode of applying my improvements to an L-head motor; and Fig. 8 is a detail sectional view 85 taken on the line 8—8 of Fig. 7 and looking in the direction of the arrows.

Describing first the parts shown in Figs. 1 and 2: 1 represents the cylinder head, 2 the valve stem, 3 the valve spring, 4 the 90 rocker bracket, 5 the rocker, and 6 the lift-rod. The rocker 5 is shown as having at one end a shoe 8 engaging the valve stem and at the opposite end a threaded socket 9 in line with the lift-rod and adapted for 95 the reception of adjusting means whereby the lost-motion is regulated. Sometimes the rocker arm is reversed in position, the adjustment being located in line with the valve stem, but the present arrangement is frequently employed and will illustrate sufficiently my invention which can be applied to either end of the rocker.

In the socket 9 I secure rigidly a longitudinally bored sleeve 10 having therein a 105 slidible plunger 11 whose lower end makes close contact with the lift rod (or valve stem as the case may be). The upper end of the sleeve has a head 12 formed at one side with ears 13, between which is pivoted 110 a link 14; while the plunger 11 is provided with a head 15 formed with an over-hang-

ing bracket 16 located directly above the ears 13 and having pivoted thereto the links 17, the free ends of which are pivoted at 18 to the first link so as to form there-
 5 with a toggle joint. The head 15 is formed with a socket 19 substantially in line with the pivot 18 and receiving a spring 20 which bears against the toggle joint so as tend to deflect the same. Upon each upward
 10 movement of the lift-rod 6 this toggle is straightened against the influence of the spring 20 and the rocker arm is then displaced, while upon the return of the lift rod the deflection of the toggle joint maintains all
 15 the parts in tension and prevents hammering. The parts are adjusted by turning the sleeve 10 so that total lost-motion of from 10/1000 to 20/1000 of an inch is permitted which is several times as great as is permissible with
 20 the plain tappet, and the permissible tolerance in the adjustment is so great that it can be effected with a minimum of skill or experience.

In the construction shown in Figs. 3 and
 25 4, the sleeve 10^a is formed at its upper end with a head 12^a having the spaced arms 13^a between which is located the head 15^a of the
 30 plunger 11^a, the last named head having the bifurcated brackets 16^a—16^a. To the ears
 35 13^a are pivoted the links 14^a—14^a and to the bracket 16^a there is pivoted the link 17^a whose free end is pivoted at 18^a to the first named links. The link 17^a is formed with the socket 19^a in which is received the spring
 40 20^a whose purpose is to deflect the links out of a straight line. The operation of the device is the same as before.

In the embodiment shown in Figs. 5 and
 45 6 the rocker is formed in two parts 30 and 31 respectively, whose meeting portions are branched so as to be pivoted upon a spindle 32, the ends of the branches being turned upwardly to form the ears 33 and 34 respectively. Links 35 and 36 are pivoted to-
 50 gether and to these ears so as to constitute a toggle joint, and a spring 37 (here shown as a compression spring) is employed to break the toggle.

In the embodiment shown in Figs. 7 and
 55 8 the valve stem 2^a and lift-rod 6^a are arranged in line with each other. To the end of the valve rod is applied a socket member 40 having lateral ears 41—41 to which are pivoted the links 42—42, while to
 60 the end of the lift rod there is applied a socket member 43 traversed by a pivot 44 to which are pivoted the links 45—45 whose free ends are pivoted at 46 to the free ends of the first links. I have here shown a
 65 spiral spring 47 wrapped around the pin 44

and engaging the links 45 to throw the same out of line and keep the parts tight, as well as retaining them in place upon their respective members.

The generic idea of my invention will be 65 sufficiently clear without further description and it will be understood that I do not limit myself to the constructions herein shown except as described in my claims and rendered necessary by the prior art. 70

Having thus described my invention what I claim is:—

1. In an internal combustion engine of the poppet valve type, the combination with a valve-stem and its lifting rod, of connecting 75 means interposed therebetween and comprising a series of links pivoted together and at their ends, and spring means tending to deflect said links laterally, said links being arranged to open the valve by a pulling action 80 when the lift-rod is raised.

2. In an internal combustion engine of the poppet valve type, the combination with a valve-stem and its lifting rod, of a movable member abutting against one of those parts, 85 a link pivoted thereto, a second member abutting against the other part, a second link pivoted to the first link and to said second member, and spring means tending to deflect said links out of a straight line whereby 90 said members are held snugly against the parts which they respectively abut.

3. In an internal combustion engine of the poppet-valve-in-head type, the combination with a valve-stem and its lift-rod, of a rocker 95 abutting against one of those parts, a relatively movable member carried by said rocker and abutting against the other of those parts and a pair of links pivoted together and to said rocker and member, re- 100 spectively, and a spring tending to move said links laterally, said links being arranged to come into tension as said rocker is moved.

4. In an internal combustion engine of the 105 poppet-valve-in-head type, the combination with a valve-stem and its lift-rod, of a rocker abutting against one of those parts, a pivot carried thereby, a relatively movable member carried by said rocker and abutting against the other of those parts, said member extending past said pivot and itself having a pivot located upon the opposite side of said first pivot from the part which said movable member abuts, and a pair of links pivoted 110 together and attached one to each of said pivots.

In testimony whereof, I hereunto affix my signature.

JAMES B. KIRBY.
